assignors to Keweenaw Manufacturing Company,
Adrian, Mich., a corporation of Michigan

Filed Jan. 23, 1962, Ser. No. 68,483

Term of patent 14 years

(Cl. D16—2)

FIGS. 1 and 2 are front and rear perspective views, respectively, of a combination special-atmosphere work station and vacuum oven embodying our novel design.

The top and bottom of the combination special-atmosphere work station and vacuum oven are substantially plain and flat. The illustration of internal elements in broken lines, behind the transparent front panel of the device, is shown for illustrative purposes only.

We claim:

The ornamental design for a combination special-atmos-

sphere work station and vacuum oven, as shown and described.
